[57] CLAIM

The ornamental design for head and neck pillow, as shown and described.

DESCRIPTION

FIG. 1 is a front view of head and neck pillow showing my new design;

FIG. 2 is a rear elevational view; the broken line showing of the strap is for environmental purposes only and forms no part of the claimed design;

FIG. 3 is a right side view (left side mirror image);

FIG. 4 is a section taken along line IV—IV of FIG. 1;

FIG. 5 is a top view;

FIG. 6 is a bottom view; and,

FIG. 7 is a perspective view.
